Houson & Houson.

UNITED STATES PATENT OFFICE.

EDWIN G. RUST, OF PHILADELPHIA, PENNSYLVANIA.

BLAST-FURNACE TOP.

1,307,884.

Specification of Letters Patent. Patented June 24, 1919.

Application filed July 16, 1918. Serial No. 245,127.

To all whom it may concern:

Be it known that I, EDWIN G. RUST, a citizen of the United States, residing in Philadelphia, Pennsylvania, have invented 5 Blast-Furnace Tops, of which the following is a specification.

One object of my invention is to so form and associate the upper part of the main lining and the dome of a blast furnace as 10 to maintain the former at the proper thickness at all points, as well as to so mount the dome that neither it nor the furnace shell shall be injured by the expansion of the lining under operating conditions. 15 It is further desired to provide a novel form of joint or connection between the body and the dome of a blast furnace which will permit of a limited relative movement of the latter under the action of expansion 20 of the furnace lining;—the invention contemplating the use of motion-limiting members which if desired, may be set up to draw down the dome to its proper position after it has been displaced therefrom. 25 These objects and other advantageous ends I attain as hereinafter set forth, reference being had to the accompanying drawings, in which—

Figure 1 is a longitudinal vertical section 30 of the top of a blast furnace showing my invention as applied thereto; and

Fig. 2 is a fragmentary vertical section illustrating on a larger scale than Fig. 1, the detail construction of the connection between the furnace shell and the lower part 35 of the dome.

In the above drawings 1 represents the upper part of the fire brick lining of a blast furnace which is inclosed by a sheet metal shell 2 spaced away from it and having a filling 3 within this space. According to 40 my invention I mount at suitably spaced intervals around the upper end of the shell 2 a series of outwardly projecting angle brackets 4 and also fix to said shell as by riveting, an angle iron 5 extending completely around it with its top flange substantially flush with the horizontal tops of the brackets 4. A flat, outwardly extending 45 ring or diaphragm 6 has its inner edge rigidly connected to this angle iron and hence to the shell 2 and is normally carried on the horizontal tops of the brackets 4 so as to serve as a support for the dome 7 of 50 the furnace which is spaced away from and incloses the upper part of the lining 1 which

is maintained of a substantially uniform thickness for its entire height. The upper part of the lining as well as of the dome is given the customary truncated conical 60 form.

The dome includes a shell or casing 9 to whose lower edge is riveted a ring of angle iron 10 which is also riveted to the outer edge of the supporting ring or diaphragm 6 and this angle iron is also loosely connected to the brackets 4 by bolts 12 of such length that the dome with its shell and diaphragm 6 may move upwardly from the positions shown in full lines in Fig. 2 to 70 those shown in dotted lines. Any further movement of these parts is prevented by the bolts 12.

The upper edge of the shell 9 of the dome carries a ring 13 for the support of the hopper 14 and this latter in turn is designed to coöperate with a bell 15 of any desired or suitable construction.

With the above described construction and arrangement of parts it will be noted that 80 the main furnace lining 1 extends to its full height without having its thickness diminished on account of the dome lining as was the case in previously constructed dome topped furnaces.

In my invention the dome lining is supported entirely outside of the substantially cylindrical surface defined by the shell 2 and is free to expand without injury either to the dome or to the shell 2. When expansion or upward movement of the furnace lining occurs, the dome with its associated parts is merely raised and caused to deflect the diaphragm 6 as shown without straining or tending to rupture the furnace shell as 90 would be the case if it were rigidly instead of yieldingly connected thereto. If for any reason said dome should not return to its proper or normal position upon contraction of the lining 1, it may be forcibly drawn 100 down by setting up the nuts on the bolts 12.

I claim:

1. The combination with the lining and shell of a blast furnace of a dome having its cylindrical part outside the substantially cylindrical surface defined by said shell; and means for movably supporting said dome from the top of the shell.
2. The combination in a blast furnace of a main lining of substantially uniform 110 thickness from bottom to top; a shell for said lining; and a dome having its lining

extending around and carried upon said main lining; with a flexible connection between the main lining and the dome, mounted to permit relative vertical movement of 5 the latter.

3. The combination with the main shell and lining of a blast furnace of a series of outwardly projecting brackets mounted on the upper part of said shell; an annular 10 plate carried by said brackets; and a dome having its lower portion supported on said plate and flexibly connected to the main shell thereby.

4. The combination with the main shell 15 and lining of a blast furnace of a series of outwardly projecting brackets mounted on the upper part of said shell; an annular plate carried by said brackets; and a dome having its lower portion supported on said 20 plate, said plate having its inner edge connected to the shell and its outer edge connected to the dome so as to be free to move up and down therewith independently of said shell.

25 5. The combination of the main lining of a blast furnace; a shell around said lining; a ring and a series of brackets mounted on the upper part of said shell; an annular plate supported on the brackets and connected to the ring; a dome including a shell and lining carried on said plate; and a second ring connecting said dome shell and the plate and movable with the dome independently of the brackets.

35 6. The combination of the main lining of a blast furnace; a shell around said lining; a ring and a series of brackets mounted on the upper part of said shell; an annular plate supported on the brackets and connected to the ring; a dome including a shell and lining carried on said plate; and a sec- 40

ond ring connecting said dome shell and the plate; with a shell for said dome lining flexibly connected to said first shell.

7. The combination of the main lining of 45 a blast furnace; a shell around said lining; a ring and a series of brackets mounted on the upper part of said shell; an annular plate supported on the brackets and connected to the ring; a dome including a shell 50 and lining carried on said plate; a second ring connecting said dome shell and the plate; with means for limiting movement of the second ring away from the brackets.

8. The combination of the main lining of 55 a blast furnace; a shell around said lining; a ring and a series of brackets mounted on the upper part of said shell; an annular plate supported on the brackets and connected to the ring; a dome including a shell and 60 lining carried on said plate; a second ring connecting said dome shell and the plate; with bolts for limiting movement of the second ring away from the brackets.

9. The combination in a blast furnace of 65 a main shell; a main lining; a dome including a lining and a shell flexibly connected to the main shell, the main lining of the furnace being of undiminished thickness adjacent the lower part of the dome. 70

10. The combination in a blast furnace of a main shell; a main lining; a dome including a lining and a shell flexibly connected to the main shell; the main lining of the furnace being of undiminished thickness adjacent the lower part of the dome; with means for limiting the vertical movement of the dome relatively to the main part of the furnace. 75

In witness whereof I affix my signature. 80

EDWIN G. RUST.
